UNITED STATES PATENT OFFICE.

EDGAR JEROME, OF NORWALK, CONNECTICUT.

TOILET-PAPER HOLDER.

1,065,910.

Specification of Letters Patent. Patented June 24, 1913.

Original application filed June 15, 1909, Serial No. 502,345. Divided and this application filed February 21, 1911. Serial No. 610,027.

To all whom it may concern:

Be it known that I, EDGAR JEROME, citizen of the United States, residing at Norwalk, Connecticut, have invented certain new and useful Improvements in Toilet-Paper Holders, of which the following is a specification.

My present invention relates particularly to suspension means for a pack of toilet paper sheets, and is a division of the subject matter disclosed in my application filed June 15, 1909, Serial Number 502,345, which has matured into Patent Number 1,046,510.

The invention consists in the features 15 hereinafter described and particularly pointed out in the claims.

In the drawings—Figure 1 is a front view 20 of a toilet paper holder, and pack of paper sheets embodying my invention. Figs. 2 and 3 perspective views of the suspension wire looking from opposite sides thereof.

In carrying out my invention I employ a base plate A, of metal, having fixed thereto standards 2—2 in which bears a spring arm 3, which carries at its end a pressure device 25 for exerting a controlling pressure upon the paper pack. This base plate A also carries an upturned flange 16 which is inclined from a horizontal plane and is open at one 30 end, or in other words, has a free space at its end adapted to receive an inclined hook 15 of a suspension wire E, which passes through the paper pack and has its front end upturned to retain the sheets of said 35 pack in place. The inclined hook portion 15 extends laterally from the vertical portion 14, and this vertical portion connects with the horizontal portion 14' of the wire, which, as stated, is turned up at its front 40 end at 14'' to retain the paper sheets. In suspending the device the hook 15 is passed over the free edge of the flange 16 and is then allowed to drop down to contact with the inner wall of said flange at its lower 45 portion to be suspended thereby, the weight of the pack naturally drawing the hook down to firmly seat itself upon the flange 16. This hook, it will be noticed from Fig. 1, is out of line with the pressure or con-

trolling device carried by the spring arm 3, 50 so that any cuttings or chips of paper falling from the paper sheets when pulled from the suspension wire will not fall upon the controlling or pressure device to obstruct its proper operation. There is a special advantage to be gained by having the recess 55 formed by the flange 16, inclined as is here represented. When the hook 15 is placed in the flange 16, it will, by reason of the force of gravity, due to the weight of the paper 60 pack and the hook, slide down into the said groove until the loop at the end of the hook forms a bearing against the upper end of the inclined flange 16. Thus any lateral swinging movement is prevented and the 65 pack is always held in proper alinement with a pressure device acting upon the pack itself. This pressure device consists of a frame B having rollers—mounted at its ends, the frame being pivoted at a point 70 intermediate of its length upon the spring arm 3, so as to rock thereon and the rollers being connected by an endless band 8 extending over their peripheries. The spring arm has its laterally bent end journaled in 75 the standards 2 and it is pressed by the spring 5 to force the pressure device against the paper. As a sheet is pulled from the pack the rollers 9 turn, and after the end 80 of the sheet leaves the upper roller this roller will still be turned because of the action of the sheet upon the lower roller and this action will be communicated to the upper roller so that the next sheet of the 85 pack will be forced downwardly beyond the other sheet of the pack so that it may be grasped by the hand to be pulled downwardly.

I claim as my invention:—

1. A suspension wire for packs of paper sheets having a horizontal portion, a vertical portion, a hook extending laterally at an inclination to the vertical portion, substantially as described.
2. A suspension wire with a portion to 95 extend through a paper pack from back to front, and turned up at its front end, said wire extending upwardly at right angles to

the first portion and having a laterally extending inclined hook to lie in a plane parallel with the plane of the back face of a paper pack, substantially as described

to receive said hook arranged at an inclination, substantially as described.

10

In testimony whereof, I affix my signature in presence of two witnesses.

EDGAR JEROME.

LOUISE SCHLAUB,
J. BELDEN HURLBUTT.

Copies of this patent may be obtained for five cents each, by addressing the "Commissioner of Patents, Washington, D. C."

It is hereby certified that in Letters Patent No. 1,065,910, granted June 24, 1913, upon the application of Edgar Jerome, of Norwalk, Connecticut, for an improvement in "Toilet-Paper Holders," an error appears in the printed specification requiring correction as follows: Page 1, line 13, for the patent number "1,046,510" read 1,046,070; and that the said Letters Patent should be read with this correction therein that the same may conform to the record of the case in the Patent Office.

Signed and sealed this 22nd day of July, A. D., 1913.

[SEAL.]

C. C. BILLINGS,

Acting Commissioner of Patents.
